UNITED STATES PATENT OFFICE.

ELGIN MORELL, OF EAST ORANGE, NEW JERSEY.

VENDING MACHINE.

Application filed July 16, 1926. Serial No. 122,949.

This invention relates to vending machines and has particular reference to a machine for dispensing boxes of matches or other merchandise of this character.

Up to the present time vending machines for this purpose have invariably been provided with a discharge at or adjacent the lower end and have depended upon gravity for delivering the articles to be vended. This practice is open to the objection that in many instances the articles to be vended clog or stick and the vendee having no means of remedying such a condition, is deprived of his purchase. It has been further noted that machines constructed along such lines must of necessity be of sufficient height to afford a delivery chute or space at the lower end.

In order to overcome the above-recited objectionable features, the present invention comprehends a vending machine which is so constructed as to provide an article-removal opening at the upper end, which upon proper operation of the machine facilitates the disposal of the article in a convenient position to be removed by the vendee without depending upon gravity for the discharge of the article.

The invention furthermore contemplates a vending machine which due to the delivery of the articles from its upper end, eliminates the necessity of providing a delivery chute or space at the lower end thereby minimizing the height of the machine.

The invention aims as a still further object to provide a vending machine which is comparatively simple in its construction, economical to produce and which is highly efficient in its purpose.

With the above-recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a face view of a vending machine constructed in accordance with the invention;

Fig. 2 is a fragmentary vertical sectional view therethrough.

Referring to the drawings by characters of reference, the machine includes a rear wall 10 having a substantially semi-circular upper end and a straight lower end, and provided with a marginal forwardly-projecting wall 11 defining a casing body which is open at the front and adapted to be closed by a front wall 12 of substantially the same size and configuration as the rear wall. The front wall is preferably hinged at 13 to swing from a closed to an open position, or vice versa, to permit of the loading of the machine with the articles to be vended, the removal of the coins, or for effecting repairs or adjustments to the mechanism. Preferably the front wall 12 is provided with transparent panels 14 through which the vendee may observe the interior of the machine for the purpose of ascertaining whether or not the same is empty. A pair of superposed guide elements 15 and 16 preferably in the nature of rotary drums, are mounted within the casing on suitable stub shafts or spindles 17, whereby to constitute supports and guides about which a flexible conveyor element 18 is trained. The guide element or drum 15 is formed with peripheral teeth 19 and the flexible conveyor element with interengaging portions whereby positive driving connection between the drum 15 and conveyor element is had. The flexible conveyor element is preferably made up of a plurality of links 20, each of which includes an outwardly-projecting integral blade 21 so that between the blades of adjacent links an article-containing compartment 22 is defined.

A suitable coin-operated mechanism 23 of any desired type is arranged within the casing and is provided with a pinion 24 meshing with the teeth 19 of the drum 15 and provided with a manipulating handle 25, which upon insertion of a coin in the coin slot 26, allows the vendee to turn the pinion and the drum 15 a sufficient distance to move the flexible conveyor element a distance equal to the length of one compartment 22.

The upper ends of the front and rear walls are provided with registering notches 27 and 28, which conform approximately to the size and configuration of one of the compartments defined by the blades and links of the conveyor element. The marginal wall

11 at this point is cut away at 29 and the edges of the cutaway portion are rolled to form a smooth bead 30.

In use and operation the articles A to be vended are loaded in all of the compartments 22 of the conveyor element except the one which is initially in registry with the delivery notches. The vendee upon insertion of the proper coin in the coin slot 26, manipulates the handle 25 of the coin-operated mechanism, which imparts rotary movement to the pinion 24 and the drum 15, moving the conveyor 18 a distance equal to the length of one compartment 22. This disposes an article-filled compartment 22 in registry with the notches 27 and 28 of the front and rear walls and the cutaway portion 29 of the marginal wall 11, where the article is in a convenient position for direct grasping and removal by the vendee, thus precluding any possibility of the sticking or clogging of the article to deprive the vendee of his purchase.

What is claimed is:

- 23 1. A vending machine having means for releasing contained articles by movement laterally or outwardly, including a casing having a marginal wall with a cut-away portion providing a space, and side walls adjoining the edges of the marginal wall having notches matching said cut-away portion and defining with said space an opening communicating with the interior of the casing.
- 25 2. A vending machine for releasing contained articles by movement laterally toward either side thereof including a casing having a marginal wall with a cut-away portion at the top providing a space, and side walls adjoining the edges of the marginal wall having notches matching said cut-away portion and defining with said space an opening communicating with the interior of the casing.
- 45 3. A vending machine having means for releasing contained articles by movement laterally toward either side thereof including a casing having a marginal wall with a cut-away portion providing a space, and side walls adjoining the edges of the marginal wall having notches matching said cut-away

portion and defining with said space an opening communicating with the interior of the casing.

4. A vending machine, a casing comprising a marginal wall which is flattened at one extremity to provide a stand and being of rounded configuration at the other extremity at which it has a cut-away portion defining a space, a pair of side walls conforming to the shape of the marginal wall having notches at the top coinciding with said cut-away portion and providing an opening which with said space provides access to the interior of the casing and for the lateral abstraction of an article to be vended, and hinges for one of said side walls.

5. A vending machine comprising a casing having side and marginal enclosure walls, said walls being cut-away at a point where gravitational discharge of the articles is prevented to form a notch opening laterally and outwardly, a conveyor mounted in said casing, said conveyor having blades extending across said casing and outwardly to a point adjacent the marginal walls thereof, said blades being spaced a distance substantially equal to the width of said notch opening whereby said blades will form side walls for said notch opening when an article is dispensed from said machine.

6. A vending machine comprising a casing having side and marginal enclosure walls, the said walls being cut-away at a point where gravitational discharge of the articles is prevented to form a notch opening laterally and outwardly, a guide element located adjacent to each extremity of the casing, and a conveyor mounted upon said guide elements comprising a plurality of links hinged together, each including an outwardly projecting blade, said blades extending outwardly across said casing to a point adjacent the marginal walls thereof, the spacing of said blades being substantially equal to the width of said notch opening whereby said blades will form side walls for said notch opening when an article is dispensed from said machine.
